UNITED STATES PATENT OFFICE.

MICHAEL C. KEEFE, OF SALT LAKE CITY, UTAH, ASSIGNOR TO KEEFE CONSOLIDATED RAILWAY TIME SAVING CO., OF SALT LAKE CITY, UTAH.

CATCHER AND DELIVERY SYSTEM FOR RAILWAYS.

No. 896,024.

Specification of Letters Patent.

Patented Aug. 11, 1908.

Application filed December 16, 1907. Serial No. 406,625.

To all whom it may concern:

Be it known that I, MICHAEL C. KEEFE, a citizen of the United States, residing at Salt Lake City, in the county of Salt Lake and State of Utah, have invented new and useful Improvements in Catcher and Delivery Systems for Railways, of which the following is a specification.

My invention relates to catcher and delivery systems for railways, and has for its object improvements in the devices for delivering articles to or receiving them from moving trains.

In the accompanying drawings:—Figure 1 is an elevation of the apparatus at the station, the lower portion of the apparatus being in section. Fig. 2 is an enlarged section of the lower portion of Fig. 1. Fig. 3 is the section on line 3—3 of Fig. 2. Fig. 4 is a plan of the catcher located at the station. Fig. 5 is an enlarged section on line 5—5 of Fig. 1. Fig. 6 is an elevation of operating devices secured to the side of a train, said devices being shown in operative position. Fig. 7 is a similar view with the devices thrown out of operative position. Fig. 8 is a rear view of Fig. 7. Fig. 9 is a side elevation of the structure shown in Fig. 8. Fig. 10 is a plan of the catcher fork used on the trains for catching rings from the device shown in Fig. 1. Fig. 11 is a modified form of Fig. 10. Fig. 12 is a section on line 12—12 of Fig. 9. Fig. 13 is an enlarged detail of a portion of Fig. 12; and, Fig. 14 is a section on line 14—14 of Fig. 6.

The device of the station consists of a base 20, upon which is mounted a standard composed of an outer member or tube 21 and an inner member or rod 22 and both mounted to rotate in bearings in the base 20.

Secured to the tube 21 is a ring 23, on which is pivoted a lever 24 (see Fig. 5) which lever serves to rotate the tube 21. Grooves 25 in the top part of the base 20 are arranged so that the lever 24 may drop into them and hold the standard in either one of two positions, said positions being one-half rotation of the tube 21.

On the inner side of the tube 21, is secured a key or lug 26 (see Fig. 3) and secured in the inner stem 22, are a series of pins 27, arranged in two rows on opposite sides of the key 26. This key and these pins are so arranged that when the tube 21 is turned one-half revolution by hand, as described, from

one position to another, the key 26 engaging the pins 27, will cause the stem 22 to turn only one-quarter of a revolution.

On the standard 21 are three clamps 28, 29 and 30, which may be adjusted vertically on the said standard by loosening the clamp bolts and securing them at any desired position. Secured to the clamp 28 is a branch catcher or horn 31, the branches of which extend laterally as shown in Figs. 1 and 4. These horns are for the purpose of catching the rings from a passing train, a horn entering a ring upon the train at the time the train passes. On the clamps 29 and 30 are ring holders 32, provided with springs 33 for holding rings 34. These parts are so arranged that when a ring is pushed in between the springs 33, said springs will hold the rings against a considerable vertical strain, but the ring is easily removed by a lateral strain.

At the top of the standard and secured to the inner stem 22, is a lamp 35, provided with color lights facing in four directions. The glass which produces the color of these lights is preferably of the same color on two opposite sides, and of a different color on the two other opposite sides. The result of this is that when the stem 22 is in one position, it shows a light of a particular color in both directions down the track. When the stem has been moved through one-quarter of a revolution, a different colored light shows in both directions. When the outer shell or tube 21 is in the position shown in Fig. 1, the device would be in operative position for a train passing at the right of Fig. 1, as shown. By means of the lever 24, the outer tube may be turned through one-half of a revolution and the rings 34 and catcher 31, will be turned away from a passing train. In this turning of the outer shell through one-half of a revolution, the inner stem will be turned through one-quarter of a revolution, as previously described, and will bring a different colored light into view from a passing train. As thus made, the mere act of moving the catching or delivery devices of the station into an operative position, results in automatically shifting the position of the light 35 so as to indicate to the engineer or the conductor of a passing train whether or not packages or articles are to be delivered from the station to the train.

The coöoperating devices on the train con-

sist of a frame 36, which is secured to the side of the engine or one of the cars, 50, of the train and upon which are supported suitable ring holding and ring catching devices.

- 5 At the upper end of the frame 36 is a vertical pivoting pin 37, upon which is secured a ring holding device 38, which, except for the manner of securing it, is the same as the ring holding device 32, previously described.
- 10 The rear part of the ring holding device 38 extends through an opening in the frame 36 and is pivoted to a link 39, by way of which the ring holding device 38 may be moved into or out of operative position.
- 15 At the lower portion of the frame 36 is a horizontal pin 40, to which is pivoted a fork 41, which fork is V-shaped and is bent around at right angles so that the plane of the V- is substantially parallel to the axis of the pin
- 20 40. The rear portion of the fork 41 also extends through an opening in the frame 36 and is pivoted to a link 42. A bell crank 43 is pivoted to the frame 36 at the point 44 and is connected to the links 39 and 42 so that by
- 25 moving the bell crank by hand on its pivot, the ring holder 38 and the catcher 41 are both turned upon their pivots. The connections are such that when turned in one direction, both the ring holder and the catcher are
- 30 in operative position, but when turned in the other direction, both are out of operative position. When in operative position, the catcher lies horizontally, as shown in Figs. 9 and 14. When out of operative position, the
- 35 catcher is in a vertical position as shown in Fig. 7.

The arms or branches of the catcher 41 have secured to them springs 43, which are arranged as shown in Fig. 10. These springs 40 incline inward so as to make a reentrant angle. The springs are of different tension; those at the outer portion being of comparatively light tension and those at the inner portion being comparatively stiff and of high 45 tension. The springs are preferably arranged so that each pair consisting of one spring from each branch, is of slightly greater tension than the next outer pair.

In operation the free ends of the springs 50 engage a ring which pushes these springs inward and permits the ring to enter within the V- of the catcher. Immediately upon the ring passing the springs, the free ends of the springs of opposite sides come again in contact with each other as shown in Fig. 10, and prevent the ring from being dropped out accidentally. The ring is easily removed by simply forcing another portion of the ring inward through the springs so that the ring 55 rests inside of the V- as if it had been placed there from a direction perpendicular to the plane of the V- and without passing through the springs.

In Fig. 11 is shown a modified form of 60 spring arrangement 44 for receiving and

holding a ring. In this case there is but one spring, the two ends of which are fastened to the opposite branch of the catcher and form the spring V- as shown.

What I claim is:—

1. A tubular standard, catching and delivering devices supported thereby, a second standard disposed within said tubular standard a signal lamp supported by said inner standard, means by which the respective standards may be rotated so as to bring the catching and delivering devices into or out of operative position and to dispose the signal lamp in position to indicate the position of the catching and delivering devices.

2. The combination with a revoluble standard, of a signal lamp carried upon the upper end thereof, a revoluble casing inclosing said standard, catching and delivering devices carried by said casing, and means for operative connection between said standard and its casing whereby said standard may be affected by part of the motion of said casing.

3. The combination with a revoluble standard, of a signal lamp carried thereby, a revoluble tube inclosing said standard, catching and delivering devices carried by said tube, a projection extending inwardly from said tube, and a member carried by said standard in the path of said projection whereby said standard is affected by part of the motion of said tube.

4. In a catching and delivering device for railway stations, a standard consisting of an inner stem and an outer tube, a base upon which said standard is supported, a hand lever secured to said tube and serving as means by which an operator may turn the tube, and connections between said tube and said stem so arranged that a half turn of the 100 tube causes a quarter turn of the stem.

5. In a catching and delivering device for railway stations, a standard consisting of a revoluble tube and a revoluble standard disposed therewithin, a lever by which said tube may be turned on its axis, and means for operative connection between said tubes and standards so arranged that a half turn given to said tube causes a quarter turn to said standard.

6. In a catching and delivering device, a rotatable standard, a pair of clamping members secured together and upon said standard and a ring holding device carried by one of said clamping members.

7. In a catching and delivering device, a rotatable standard, a plurality of clamps adjustably secured upon said standard, each of said clamps consisting of a pair of clamping members and means for securing the same together, and a ring holding device carried by one member of each of said clamps.

8. A catching device consisting of a standard two metallic horns projecting upwardly and laterally in opposite directions from said

- standard, means by which said standard may be turned to bring said horns toward or away from a passing train, and a signal lamp for indicating the position of said horns.
- 5 9. The combination with a delivery ring and means for supporting it at a station, of a catcher secured to a passing train, said catcher consisting of a fork for initially engaging the ring and springs extending inwardly from each arm of the fork.
10. In a ring catching and delivering device for trains, a frame provided with horizontal and vertical pivoting pins, a catching fork mounted upon the horizontal pin and having its branches extending laterally in a plane substantially parallel with the pin, a ring holder mounted on the vertical pin, a bell-crank lever, link connections between said bell-crank lever and said catching fork and ring holder, and means for moving said bell-crank lever to turn the catcher and the holder upon their pivots so as to move them into and out of operative position.
11. A V-shaped catcher having a plurality of inwardly inclined springs connected to each branch of the V, the inner springs being of greater tension than the outer springs.
12. In a catching and delivering device, the combination with a base, of a tube rotatably mounted in and extending upwardly from said base, catching and delivering means secured upon said tube, a standard rotatably disposed within said tube and in said base, a signal carried by said standard above said tube, and means whereby said standard is affected by part of rotary movement imparted to said tube.
13. In a catching and delivering device, the combination with a base, of a tube mounted rotatably in and extending upwardly from said base, catching and delivering means secured upon said tube, a handle movably secured to said tube, means whereby said handle may engage with said base at definite points to determine the position of said tube, a standard rotatably disposed within said tube and in said base, a signal carried by said standard above said tube, and means whereby said standard is affected by part of rotary movement imparted to said tube.
14. In a catching and delivering device, the combination with a base, of a standard
- rotatably mounted in said base, a collar on said standard, a tube surrounding said standard and resting on said collar, said tube being movable relative to said base and said standard a signal carried by said standard, catching and delivering means carried by said tube, means whereby said standard is affected by part of rotary movement imparted to said tube, and means for locking said tube to said base in predetermined positions.
15. In a catching and delivering device, the combination with a base of a tube rotatably mounted in and extending upwardly from said base, catching and delivering means secured upon said tube, a standard rotatably disposed within said tube and in said base, a signal carried by said standard above said tube, an engaging member on the inside of said tube, and an engaging member on said standard in the path of said first named engaging member whereby said standard is affected by part of rotary movement imparted to said tube.
16. In a catching and delivering device, the combination with a supporting plate, of a delivering member pivoted to said plate, to swing horizontally, a catching member pivoted to said plate to swing vertically, extensions on said delivering and catching members extending through openings in said plate, a bell-crank lever pivoted to said plate, and links connecting said bell-crank lever with said extensions.
17. In a catching and delivering device, the combination with a supporting plate, of a delivering member pivoted to said plate to swing horizontally, a catching member pivoted to said plate to swing vertically, extensions on said delivering and catching members extending through openings in said plate, a bell-crank lever pivoted to said plate, links connecting said bell-crank lever with said extensions, and a handle on said bell-crank lever for moving the same to operate said catching and delivering members.
- In testimony whereof I have signed my name to this specification in the presence of two subscribing witnesses.
